(57) **CLAIM**

The ornamental design for a neck cushion for automobile, as shown and described.

DESCRIPTION

FIG. 1 is a front, top, and right side perspective view of a neck cushion according to an embodiment of the present invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a reference view illustrating a neck cushion of FIG. 1 connected to an automobile chair.

The design is of a neck cushion for an automobile intended for use as a neck cushion for an automobile. The broken lines used in the drawings are for the purpose of illustrating environmental structure and form no part of the claimed design.
